TION OF NEW JERSEY.

WIRE-ROPE COUPLING.

1,121,736.

Specification of Letters Patent. Patented Dec. 22, 1914.

Application filed July 16, 1914. Serial No. 851,300.

To all whom it may concern:

Be it known that we, JAMES G. LEE and CHARLES C. SUNDERLAND, citizens of the United States, residing at Trenton, county of Mercer, and State of New Jersey, have 5 invented certain new and useful Improvements in Wire-Rope Couplings, fully described and represented in the following specification and the accompanying drawings, forming a part of the same.

10 This invention relates to an improved coupling intended particularly for small wire ropes or cords having a fiber covering, usually braided or woven, the especial object of the invention being to provide an efficient 15 and durable coupling for bell-cords and similar cords running over small pulleys, in which great flexibility is required and it is important to avoid undue wear on the fiber covering of the wire.

20 In the accompanying drawing forming a part of this specification there is shown, for purposes of illustration, a portion of a bell-cord with a coupling embodying all the features of the invention in their preferred 25 form, and this construction will now be described in detail, and the features forming the invention then specifically pointed out in the claims.

30 In the drawing—Figure 1 is a side view of the cord and coupling, and Fig. 2 is a similar view on an enlarged scale taken at right angles to Fig. 1, and with the coupling in section.

35 Referring to the drawing, *a* is the wire rope or center of the bell-cord, and *b* a braided thread cover. The coupling consists of the sockets *c*, screw-threaded at one 40 end to receive the cover *b* and having the coned recess 2 at the other end receiving the wire center *a*, this end of the socket also being threaded outside at 3 to enter the cap *d*. The cap is screw-threaded at 4 to receive the socket, and carries eye *e* which preferably is 45 formed of a wire inserted through end openings in the cap *d* and headed down inside the cap by a die, or otherwise, as shown. The socket, cap and eye forming the two coupling pieces are the same at both ends of 50 the cord to be coupled, so that the above description and references apply to both. The two caps *d* are connected by a suitable flexible link, preferably one or more endless wire rope gromets, a single gromet *f* being 55 shown, as such gromets have greater flexi-

bility and durability than ordinary solid-wire links, but links of any other suitable form and construction may be used. The gromets *f* and eyes *e* are preferably made of high carbon steel for strength and long life 60 of the coupling. These bell-cords must operate over very small pulleys and, in addition to such a link connection *f* as to give great flexibility, it is desirable to reduce the bend of the cord where it enters the sockets *c* 65 as far as possible, and for this purpose the caps *d* are coned or tapered on the outside, as shown at 5 in the drawing, thus increasing largely the life of the bell-cord.

The method of applying the coupling will 70 be understood from a brief description in connection with the drawing: The braided cover *b* is removed from the ends of the cord, together with the cotton center usually employed, and the strands and the wires 75 of the strands forming the rope center *a* are separated and spread out evenly, and then they are gathered together and passed through the sockets *c*, and the sockets screwed on over braided covers *b*. The wires are 80 then spread out to cone-shape in the coned or tapered recesses 2 of the sockets, and then soldered in by filling the spaces within the coned recesses 2 with solder, and cut or filed off evenly. The sockets are then secured on 85 the cover *b*, preferably by pinching in or crimping the sockets to form crimps 6, preferably both at the outer end of the socket and midway of its screw-threads, so as to grip the braided cover *b*. This is especially 90 desirable because the cords will vary in diameter. The caps *d* are then screwed on the ends of the sockets, solder being 95 preferably run in around the threads so as to lock the caps to the sockets, although other suitable means for locking the caps may be used. It will be understood that the two caps *d*, *d*, with their eyes *e*, are connected by the gromet or other link connection *f*, before the sockets are connected to the caps. 100

What we claim is:

1. A coupling for covered wire rope or cord, consisting of sockets screwing onto the cover of the rope and having recesses in which the wire centers are spread and secured, and caps screwing onto the sockets and provided with eyes having a flexible link connection. 105

2. A coupling for covered wire rope or cord, consisting of sockets screwing onto the 110

cover of the rope and having recesses in which the wire centers are spread and secured, caps screwing onto the sockets and provided with eyes, and a wire rope gromet connection between said eyes.

3. A coupling for covered wire rope or cord, consisting of sockets screwing onto the cover of the rope and having recesses in which the wire centers are spread and secured, and caps screwing onto the sockets and provided with eyes having a flexible link connection, said caps having their out-

side surfaces tapering inward toward the sockets to reduce the bend of the rope where it enters the sockets in running over pulleys. 15

In testimony whereof, we have hereunto set our hands, in the presence of two subscribing witnesses.

JAMES G. LEE.

CHARLES C. SUNDERLAND.
